UNITED STATES PATENT OFFICE

WALDEMAR KOPS, OF NEW YORK, N. Y., ASSIGNOR TO KOPS BROS. INC., OF NEW YORK,
N. Y., A CORPORATION OF NEW YORK

APPAREL GARMENT

Application filed October 2, 1928. Serial No. 309,721.

This invention relates to that type of apparel garment made in the nature of a corset to extend from a position above the bust line to a position below the hips and to surround the body of the wearer. The object of the invention is the provision of a garment in which there is a girdle so constructed that the front portion thereof functions as an adjustable abdominal support and diaphragm control, while the rear or back portion thereof functions as a buttocks confiner.

In carrying out the invention the garment made in accordance therewith comprises a body member which is preferably open at one side and the edges of the closure provided with means for connecting the same to one another. The body of the garment is designed to extend from above the bust line to below the hips of the wearer and is constructed to include a girdle surrounding the body of the wearer with the parts of the girdle preferably connected at the front and with the back or rear of the girdle incorporated in the lower portion of the body member of the garment. The front and side portions of the girdle, are, therefore, free from and underlie the adjacent portions of the body of the garment and are adapted to overlie the abdomen and the lower portion of the diaphragm of the body of the wearer. The girdle, furthermore, is constructed to include elastic inserts and adjustable elastic straps whereby the front portion thereof is adapted to support the abdomen of the wearer and to mold or control the lower portion of the diaphragm of the wearer, and as hereinbefore stated the back or rear portions of the girdle are made to conform to and retain the buttocks of the wearer. Furthermore, as preferably constructed the portions of the body of the garment overlying the front members of the girdle are unattached thereto in order to produce a straight front effect, all of which will be hereinafter more particularly described.

In the drawing Figure 1 is a perspective view of the garment made in accordance with this invention showing the same in position on the body of the wearer,

Fig. 2 is a front elevation of the garment showing the body member thereof open to

more clearly illustrate the girdle construction, Fig. 3 is a front elevation of the front member of the girdle, and

Fig. 4 is a plan of the garment on an enlarged scale and viewing the same in an extended position from the inner side thereof.

In carrying out the invention the garment made in accordance therewith, as will be seen by reference to the drawing, comprises a body member built up of a back member, side members, and a front member, and with which the girdle feature is incorporated. As illustrated the back member of the body of the garment includes a central section 10 and lateral sections 11 and 12. The central section 10 is connected to the lateral section 11 by a suitable reinforcing strip 13 and lines of stitching 14. This reinforcing strip 13 forms a pocket in which there are suitable stays 15. Similarly the section 12 is connected to the central section 10 by a reinforcing strip 16 and suitable lines of stitching 17. The reinforcing strip 16 forms a pocket in which are contained suitable stays 18.

The side member of the body of the garment at the right side thereof is constructed to include sections 19 and 20. The section 20 includes an elastic insert 20' extending upwardly from the lower edge of the garment to a point at or appreciably above the waist line. This elastic insert tapers from the lower edge of the garment upwardly. The sections 19 and 20 of this side member are connected by a reinforcing strip 21 and suitable lines of stitching 22. Similarly the upper portion of the section 20 and the adjacent edge of the elastic insert 20' are connected to the lateral section 11 of the back member by a reinforcing strip 23 and lines of stitching 24. The reinforcing strip 23 also provides a pocket for containing suitable stays as indicated at 25. The adjacent edges of the section 20 and the insert 20' are also connected by a reinforcing strip and the necessary lines of stitching.

The front member of the body of the garment is indicated at 26. In the lower portion of this member there is preferably employed a V-shaped elastic insert designated at 27 and also associated therewith is a liner member 28 which is adapted to extend over the central

abdominal portion of the body of the wearer.

The left side of the body of the garment includes a side section 29 and a side section 30 between which parts the garment is open and by which through a suitable closure structure it is secured in position on the body of the wearer. The section 19 of the right hand side member is connected to the front member 26 by a reinforcing strip 31 and suitable lines 10 of stitching 32. In like manner at the opposite edge thereof this front member 26 is connected to the left hand side member 29 by a reinforcing strip 33 and suitable lines of stitching 34. Along its free edge the section 15 29 is fitted with a reinforcing strip 35 which may be connected thereto by lines of stitching 36 or otherwise.

Suitably secured in spaced positions along a reinforcing strip 35 there is a series of hooks 20 37. The other section of the left hand side member, namely, the section 30, is connected to the section 12 by a reinforcing strip 38 and suitable lines of stitching 39. The section 30 corresponds to the section 20. The section 30 25 is made to include an elastic insert 30'. The adjacent edge of this elastic insert 30' is connected to the section 12 by the same reinforcing strip 38 and lines of stitching 39 by which the upper portion of the section 30 is connected thereto, and the adjacent lower edges of the section 30 and the elastic insert 30' are connected to each other by a suitable reinforcing strip and the necessary lines of stitching. This elastic section 30' is similarly shaped and 35 complementary to the elastic section 20'. The pocket formed by the reinforcing strip 38 as illustrated may contain suitable stays 40 which in this side of the garment are the counter-parts of the stays 25 in the other side 40 thereof. The free edge of the section 30 is fitted with a reinforcing strip 41 secured thereto by suitable lines of stitching 42 or otherwise and connected to the reinforcing strip 41 there is a series of eyes 43 corresponding 45 in number and position with the hooks 37 whereby, as will be understood, each one of the hooks 37 may be caused to engage in the corresponding eye 43 in connecting the parts of the closure member to secure the garment 50 in position on the body of the wearer.

In the back of the garment and associated with the lateral section 11 I employ a liner member 44 forming part of the girdle. In a centrally disposed position extending longitudinally of the garment this liner member 44 may be fitted with a reinforcing strip 45 forming a pocket for the stays as indicated at 46. The lower edge of this liner member 44 is coincident with and connected to the lower edge 60 of the lateral section 11 so that the lower edges of these sections lie in the lower edge of the garment.

The upper edge of this liner member is indicated at 47 and extends upwardly from 65 the central section 10 across the lateral section

11 to the section 20. The rearward edge of this liner member 44 is connected to the back member 10 by the same lines of stitching 14 that connect the reinforcing strip 13 thereto while the forward edge of the liner member 44 is connected to the section 20 and the elastic member 20' by the lines of stitching 24 and the reinforcing strip 23. Similarly in the left side of the body of the garment there is a liner member 48. In a central longitudinally disposed position this liner member 48 may be provided with a reinforcing strip 49 forming a pocket for suitable stays 50. The lower edge of this liner member 48 is coincident with the lower edge of the section 12, both of which lie in the lower edge of the garment. The upper edge of the liner member 48, as indicated at 51, extends in an inclined direction upwardly from the central section 10 to the section 30. The lower ends of these upper edge portions 55 of the liner members lie at or appreciably below the waist line while the upper ends thereof are approximately at or appreciably above the waist line. In the lower portion of the back of the garment there is a liner member 52 which is coextensive circumferentially with the central section 10 and extends upwardly from the lower edge of the garment an appreciable distance. The longitudinal edges of this liner member 52 are secured in the garment by the reinforcing strips and lines of stitching which secure the central section 10 to the lateral sections 11 and 12. The lower edge of the liner member 52 is connected to and coincident with the lower edge of the section 10. The upper portion of this liner member 52 like the liner members 44 and 48 is not connected to the overlying portion of the body of the garment. These liner members, as will be understood, form the rear or back 100 portions of the girdle of the garment.

The front and side portions of the girdle of the garment are preferably made in two parts divided and adapted to be connected at the front center thereof. The right hand portion of these front and side members of the girdle is preferably constructed to include a front member and a side member. The front member comprises a central or front section 53 and an elastic section 54. The section 53 may be constructed to include a reinforcing strip 55 forming a pocket for suitable stays 56. At the forward or free edge of the section 53 the same is fitted with a front steel 57 including the usual front steel sockets 58. The lower end of the front steel terminates appreciably above the lower end of the section 53 and below the front steel and at the free edge thereof this section, as illustrated, is provided with a set of hooks indicated at 59. The elastic section 54 is connected at its forward edge to the rearward edge of the section 53 by a reinforcing strip 60 and suitable lines of stitching which, as illustrated, form a pocket for a stay 61. The side member of this portion of the

girdle includes a section 62 and a section 63. These sections are connected by a reinforcing strip 64 and suitable lines of stitching 65 and the rearward edge of the elastic section 54 is connected to the forward edge of the section 62 by a reinforcing strip 66 and lines of stitching 67 which may also form a pocket for a stay 68. The upper edge 69 of the sections 62 and 63 inclines downwardly from the section 11 to the upper edge of the elastic section 54 while the lower edge 70 of these sections 62 and 63 tapers downwardly from the elastic section 54 to approximately the lower edge of the garment at the forward edge of the section 11 and the upper portion of this lower edge 70 extends to the groin of the wearer.

An anchor strap 71 is secured along one edge to the sections 62 and the elastic section 54 by the reinforcing strip 66 and the lines of stitching 67 which connect these parts to one another. At its opposite or forward edge this anchor strap 71 is provided with a series of eyelets 72. An abdominal or uplift strap 73 is secured at one end to the front steel section, as indicated at 74, with the upper portion of the forward edge at approximately the lower end of the front steel. The opposite or rearward edge of this abdominal strap, which is made of elastic webbing, is provided with a series of eyelets 75 through which, and also through the eyelets 72, a suitable lace 76 is threaded in order to adjustably connect the elastic strap 73 to the anchor strap 71. In the upper portion of the front of the girdle there is an elastic strap 77. At its forward edge this elastic strap is fixed to the front steel section by being connected thereto in any suitable manner, as for example, by lines of stitching, as indicated at 78. This strap tapers downwardly and at its rearward edge is provided with a series of eyelets 79. Threaded through the eyelets and also through the upper eyelets in the anchor strap 71 there is a lace 80 for adjustably connecting the strap 77 to the anchor strap 71.

The front members of the girdle in the left hand side of the garment are the counterparts of those hereinbefore described for the right hand side of the garment. The front member of this left hand part of the girdle comprises a section 81 and an elastic section 82. In the section 81 there is a reinforcing strip 83 forming a pocket for suitable stays 84. At the forward edge of the section 81 there is a front steel section in which the usual front steel 85 is embodied. This front steel 85 is fitted with studs 86 adapted to be received in the corresponding sockets 58 in order to thereby connect these parts of the garment.

The lower end of the front steel terminates an appreciable distance above the lower edge of the front section 81 and below the lower edge of this front steel the front steel section is fitted with eyelets 87 for engagement

with the hook members 59 in order to complete the connection between these parts of the girdle. The forward edge of the elastic section 82 is connected to the rearward edge of the section 81 by means of a reinforcing strip 88 and suitable lines of stitching which form a pocket for a stay 89. The side member of this portion of the girdle, as illustrated, comprises sections 90 and 91. These sections are connected to one another by means of a reinforcing strip 92 and lines of stitching 93 while the forward edge of the section 90 is connected to the rearward edge of the elastic section 82 by a reinforcing strip 94 and lines of stitching 95 which provide a pocket for a stay 96. The upper edge of the sections 90 and 91 is indicated at 97 and the lower edge of these sections is indicated at 98. The upper edge 97 tapers downwardly from the section 12 to the elastic section 82 and the lower edge 98 tapers upwardly from the section 12 adjacent the lower edge of the garment to the elastic section 82, the upper portion of this edge 98 extending to the groin line of the wearer.

At one longitudinal edge an anchor strap 99 is connected to the elastic section 82 and the section 90 by means of the reinforcing strip 94 and the lines of stitching which connect these sections. At its opposite or forward edge this anchor strap 99 is provided with a series of eyelets 100. An abdominal uplift strap 101 is connected at its forward edge to the lower portion of the front steel section, as indicated at 102, and this strap 101, which is made of elastic webbing, extends upwardly like the strap 73 and at its rearward edge is fitted with a series of eyelets 103. Threaded through the eyelets 103 and the lower eyelets 100 there is a lace 104 for adjustably connecting these parts to one another. In the upper portion of the girdle at the front side thereof there is a strap 105 also made of elastic webbing and secured at its forward end to the upper portion of the front steel section as indicated at 106. This strap 105 extends downwardly and at its rearward edge is fitted with a series of eyelets 107. A lace 108 is threaded through the eyelets 107 and the upper eyelets 100 in the anchor strap 99.

A garment furthermore may be provided with suitable hose supporters. As illustrated, depending from the back member there are hose supporters 109 and 110 while depending from the front portion of the garment there are hose supporters 111 and 112. Also as illustrated the garment may be fitted with suitable shoulder straps, as indicated respectively at 113 and 114.

As will now be understood, when the garment is placed on the body of the wearer the elastic uplift straps 73 and 101 may be adjusted to position to exert the necessary tension against the abdomen to adequately support the same. This tension in some instances

has the tendency of causing the upper front portion of the girdle to protrude or extend outwardly. The straps 77 and 105 are employed to overcome this difficulty and also at the same time to function as a means for controlling the lower portions of the diaphragm of the wearer. These parts are preferably made adjustable, not only in order to cause them to exert the necessary varying degrees of tension to adequately perform their functions, but also to act as a take-up as the elastic material becomes more and more less effective in the use of the garment. It will furthermore be understood that in addition to these functions performed by the front parts of the girdle, the tension exerted thereby will be extended through the side sections of the girdle and the back sections thereof to the lower rear edge portions of the garment to shape and control the buttocks of the wearer, the elastic sections 20' and 30' being employed to cause the garment to fit smoothly over the hips. Still furthermore, and inasmuch as the front and side members of the front portion of the girdle are entirely free from the garment the overlying portions thereof tend to produce a straight front effect.

I claim as my invention:—

1. In an apparel garment, a body member adapted to surround the body of the wearer from a line above the bust to a line below the buttocks, the said body member including a back section, an abdominal support and diaphragm control member comprising a front section of inelastic material and elastic sections laterally thereof, the said sections being adapted to overlie the abdomen and the lower portion of the diaphragm of the wearer, uplift straps of elastic material extending from the lower front central portions of the abdominal support and diaphragm control member to the distant edges thereof, means for adjusting the said uplift straps to position, diaphragm control straps of elastic material extending from the upper front central portion of the said abdominal support and diaphragm control member to the distant edges thereof, means for adjusting the said diaphragm control straps to position, and side sections of inelastic material connected at their forward edges to the distant edges of the said elastic sections of the said abdominal support and diaphragm control member and also to the distant edges of the said uplift straps and diaphragm control straps and at their rear edges to the side edges of the back section of the body of the garment, the lower edges of the said side sections extending downwardly from the lower end portions of the abdominal support and diaphragm control member to substantially the lower end of the lower side portions of the back section of the body member whereby the tension is adjustably exerted to support the abdomen and

to maintain the upper front portion of the abdominal support and diaphragm control member in position and to thereby control the diaphragm, the said tension being also transmitted through the said side sections to the back section of the garment to cause the same to conform to and support the back and retain the buttocks of the wearer.

2. In an apparel garment, a body member adapted to surround the body of a wearer from a line above the bust to a line below the buttocks, the said body member including a back member, a longitudinally divided abdominal support and diaphragm control member comprising front sections of inelastic material connectible to one another and elastic sections laterally thereof, the said sections being adapted to overlie the abdomen and the lower portion of the diaphragm of the wearer, uplift straps of elastic material

extending upwardly from the lower front central portions of the abdominal support and diaphragm control member to the distant edges thereof, diaphragm control straps of elastic material extending downwardly from the upper front central portions of the said abdominal support and diaphragm control member to the distant edges thereof, side members of inelastic material connected at their forward edges to the distant edges of the said elastic sections of the said abdominal support and diaphragm control member and at their rear edges to the side edges of the back member of the body of the garment, the lower edges of the said side members extending downwardly from the lower end portions of the abdominal support and diaphragm control member to substantially the lower end of the side portions of the back member of the body member, anchor straps connected to the forward edges of the said side members, and lacing devices for adjustably connecting the said anchor straps to the said uplift straps and the said diaphragm control straps, whereby tensions is adjustably exerted to support the abdomen and to maintain the upper front portion of the abdominal support and diaphragm control member in position to control the diaphragm and the said tension is transmitted through the said side members to the back member of the garment to cause the lower portion of the back member of the garment to conform to and support the back and retain the buttocks of the wearer.

Signed by me this 25th day of September, 1928.

WALDEMAR KOPS.
